(57) **CLAIM**

The ornamental design for vertical tool container and tool rack, as shown and described.

DESCRIPTION

FIG. 1 is a perspective view of a vertical tool container and tool rack showing my new design.

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a perspective view similar to FIG. 1, in which tool trays and tool containers are shown in various positions.
